UNITED STATES PATENT OFFICE

JOSEPH CIPKO, OF NEW YORK, N. Y.

WIRE RING ROLLING MACHINE

Application filed April 6, 1931. Serial No. 527,915.

This invention relates to new and useful improvements in a wire ring rolling machine.

It is customary to manufacture lamp shades with wire rings of various diameters and gauges. It is an object of this invention to produce a machine which is capable of winding various gauges of wires to various diameter sizes so that thereafter the wound wire may be cut to form rings.

10 It is another object of this invention to produce a wire rolling machine which is characterized by a frame supporting a plurality of rotative wire winding drums at a convenient height from the floor for the comfort of the operator, and a plurality of arms pivotally mounted on said frame and supporting other sizes of winding drums, and means for holding the arms in the pivoted position to the front of the first mentioned 15 drums so as to be at the convenient height specified.

Furthermore, as another object, this invention proposes that all of the various wire winding drums previously mentioned, be removable, and provision be made to detachably hold them in place.

Another one of the objects of this invention is the arrangement of squared spindle portions on the wire winding drums for accommodating a crank for manual turning.

Another object of this invention is the provision of a chart with the machine to guide the operator in the manufacture of the wire coils of different sizes and thus save time and material.

Another one of the objects of this invention is the provision of a top winding drum capable of normally maintaining the rear position and to be movable to the front so as to be at the convenient height previously mentioned, and a bottom winding drum normally depending downwards and movable to the front and upwards to the convenient height.

Furthermore, as another object, it is proposed to provide means to hold the lower arms in place and means to release the lower arms when the drum which is set behind on the main frame is to be used.

50 Furthermore, this invention has for an-

other object the provision of a wire rolling machine which is of simple, durable construction, dependable in use, efficient in operation, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings, forming a material part of this disclosure:—

Fig. 1 is a front elevational view of a machine constructed according to this invention.

Fig. 2 is an end elevational view of Fig. 1.

Fig. 3 is a fragmentary enlarged sectional view taken on the line 3—3 of Fig. 1.

Fig. 4 is a fragmentary enlarged elevational view looking in the direction of the line 4—4 of Fig. 3.

Fig. 5 is a fragmentary elevational view looking in the direction of the line 5—5 of Fig. 1.

Figs. 6 and 7 are elevational views of the wire drums used in the device.

Fig. 8 is a fragmentary enlarged sectional view taken on the line 8—8 of Fig. 2.

Fig. 9 is a fragmentary elevational view looking in the direction of the line 9—9 of Fig. 1.

Fig. 10 is a perspective view of the product of the machine upon a jig.

Fig. 11 is a chart for use in conjunction with the machine to save time.

The wire rolling machine comprises a frame 10 which is of substantially U-shaped form and is mounted upon a stand 11. The U-shaped member has a pair of vertical arms indicated by reference numerals 12.

A plurality of wire winding drums 15 and 16 are rotatively mounted in the arms 12 at a convenient height from the floor so that the operator may work in comfort. Each of these drums are rotatively mounted in apertures 56 formed in the right arm 12 while in the left arm 12 they engage in slots 57 so that only one of the ends may be removed to

allow the removal of coils wound upon the drum. Catches 19 are pivotally mounted upon the left arm 12 in the vicinity of the slots 57 and are adapted to engage over the spindles of the drums so as to normally hold the drums in place.

The drums 15 and 16 because of their large diameters are very heavy and consequently it would be impractical to mount them removably at both ends, since it would be too large a job to remove them. Consequently, they are supported at all times at one of their ends and removable from the support 12 at their other ends merely for the purpose of 10 coils wound upon them. When one of the ends of the drums is lifted, only half the weight of the drum need be contended with since the other half of the weight may be supported. Trunnions 18 project from the 20 ends of the drums 15 and 16 and it is by these trunnions that the drums are supported in the arms 12.

On each of the arms 12 there is mounted an upper arm 28 which is pivotally supported 25 at 29. The arms 28 are of substantially L form with the short ends 30 extended inwards. A peg 31 is mounted in each of the arms 12 and forms a stop for the arms 28 so as to limit backward motion to the position 30 shown in full lines in Fig. 2. A wire winding drum 32 is provided with a spindle 33 which extends into a slot 28^a formed in the end of the left arm 28. Right arm 28 has merely an aperture 28^b through which the 35 spindle passes. Catch 34 is mounted upon the left arm 28 and serves to clamp the spindle 33 in place. The catch 34 comprises a member pivotally mounted at its outer end as indicated by reference numeral 35 and capable of encircling around a portion of the 40 spindle 33. A spring lock 20 is mounted upon the plate 34 engageable within an aperture formed with the arm 28 so as to keep the member 34 in its latched position.

45 A pair of lower arms 36 are pivotally mounted at 37 upon the lower portions of the arms 12 and are also of substantially L shape but have their smaller ends outside. A wire-winding drum 38 has a spindle 39 engaged in slots formed in the ends of the arms 36. A catch 19 is mounted on each of the arms 36 and serves to normally hold the spindle in place. The inner ends of the arms 36 are formed with a grooved portion 40 and 50 holes capable of being engaged by a stem 35 of a catch 20 mounted in the arms 12.

The catch 20 is clearly shown in detail in Fig. 8 wherein a casing 21 is illustrated threadedly engaged into the arm 12 or other 60 element supporting the catch and has an interior hollow 22. A spring 23 is disposed in this hollow and acts between a flange 24 on an extendible stem 25 and a front plate 26. The stem 25 is provided with a head 27 65 for manual moving.

In Fig. 6 a very small sized winding drum 58 is shown, and in Fig. 7 the next larger drum indicated by reference numeral 59. Each of the drums 15, 16, 32, 38, 58 and 59 are of different diameters and have different diameter sections as clearly shown on the drawings. Each of these sections has an aperture 15'. In all, it is contemplated to use just these six different sizes of drums. In Fig. 11 a table has been illustrated as a time saver in the use of the various drums. On the chart some of the sizes of the rings are indicated by alphabet while others are shown by numerals, the idea is that the drums 15, 16 and 32 are quite heavy and are mounted upon the machine so as not to be removable and are therefore indicated by numerals. The three drums 38, 58 and 39 are much lighter in weight and may be substituted one for the other upon the machine as is desired according to the sizes of rings to be manufactured, and to distinguish these drums from the ones which cannot be removed they are marked with letters. This arrangement helps the operator to quickly locate the drums and the sections which he wishes to use thereof without undue complications. If all of the drums were marked with numbers or if all were marked with letters, the quantity of the same types of symbols involved would cause more confusion than the arrangement proposed. In addition, the chart directs the gauge wire to be used to obtain a desired size of ring. For example, when a number 10 wire is used and it is required to make a spring having a 7" outside diameter, the section marked numeral 18 should be used.

The operation of the device may be understood by assuming the apparatus in the condition shown in Fig. 2. In this condition the lower winding drum 38 is in the act of being moved to its front position. This front position is indicated by the dot and dash lines 53. The dot and dash lines 54 indicate the front position of the drum 32. In the front position of the drum 32, the arms 28 rest against the spindles 18 so as to maintain the position. The front position of the drum 38 is maintained by the catches 20 which are located in both the arms 12 and act against the grooves 40 in the arms 36. A wire may be inserted in the aperture 15' of any of the drum sections and revolution of the drum by means of the crank 55 causes the production of a coil of wire 46. The coil of wire 46 may be engaged upon a jig 44 having a cut-out 45. Cutting of the coil along the line 47' will produce rings of wires.

When it becomes necessary to wind a coil of a certain diameter, the chart may be consulted for ascertaining which of the sections of the drums should be used. In examining Fig. 1 it will be noticed that each of the sec-

tions is provided with a different indicating numeral.

It is intended that normally the drum 32 be to the rear and the drums 38 depend downwards. Then either drum 15 or 16 may be used. In use, a crank 55 is placed on the squared end of the spindle which supports either of the drums and the drum may be turned. The crank is removable so that one crank is sufficient for the machine in that it may be engaged on any of the spindles.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms.

2. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, said frame consisting of a U-shaped member supported on a stand, and said drums being mounted between the arms of the U-shaped member.

3. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, each of said wire winding drums consisting of a plurality of sections of different diameters.

4. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, said upper arms being pivotally mounted and of L-shape, and pegs project from said frame into the path

of motion of said arms so as to hold them in the rear position.

5. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, said upper arms being pivotally mounted and of L-shape, and pegs project from said frame into the path of motion of said arms so as to hold them in the rear position, said arms being pivotal to the front to rest upon the top spindle whereby the drum assumes a front position.

6. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, said lower arms being pivotally mounted at the inner ends and being formed with grooves engageable by catches mounted upon said frame.

7. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, drums mounted on the ends of said arms, and catches for holding the arms in the various positions.

8. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, each of said wire winding drums being freeable at one end to allow removal of coils wound thereon.

9. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, and drums mounted on the ends of said arms, each of said wire winding drums being freeable at one end and means for normally holding the drums against accidental removal.

10. A wire ring rolling machine comprising a frame, a plurality of wire winding

drums rotative in said frame, upper arms pivotally mounted in said frame, means to allow said upper arms to assume a rear and front position, lower arms pivotally mounted in said frame, means to allow said lower arms to extend towards the front, drums mounted on the ends of said arms, and means for allowing complete removal of the lower drum.

11. A wire ring rolling machine comprising a frame, a plurality of wire winding drums rotative in said frame, upper arms pivotally mounted in said frame, means to allow said upper arms to assume a rear and front position, lower arms pivotally mounted in said frame, means to allow said lower arms to extend towards the front, drums mounted on the ends of said arms, means for allowing removal of the lower drum, and drums of different sizes to replace the removed drum.

20. In testimony whereof I have affixed my signature.

JOSEPH CIPKO.
